UNITED STATES PATENT OFFICE.

HENRY JOHNSON, OF DETROIT, MICHIGAN, ASSIGNOR OF ONE-HALF TO THE WOLVERINE MANUFACTURING COMPANY, OF SAME PLACE.

DESIGN FOR A TABLE-LEG.

SPECIFICATION forming part of Design No. 25,483, dated May 12, 1896.

Application filed December 30, 1895. Serial No. 573,838. Term of patent 7 years.

To all whom it may concern:

Be it known that I, HENRY JOHNSON, a citizen of the United States, residing at Detroit, in the county of Wayne and State of Michigan, have invented and produced a new and original Design for Table-Legs, of which the following is a specification, reference being had therein to the accompanying drawings.

In the drawings, Figure 1 is a side elevation of a foot for table-legs, showing my design. Fig. 2 is a top plan view thereof; and Fig. 3 is a horizontal section on line *x x*, Fig. 1.

A is a cylindrical base ornamented by a series of small circular indentations B, and vertically disposed on and extending substantially the height of the front and sides of this base are the tapering ridges in imitation of vertically-extended claws of an animal. At the top of each of these ridges or claws and surmounting the indented base A is a partly-globular enlargement C, representing fancifully the toe of the animal. These toes extend at an upward and rearward inclination from the enlargements C for a short dis-

ance and then substantially vertically along the leg proper, and about midway of the inclined portion is a second series of enlargements or swelled portions I, giving the whole somewhat the appearance of a double foot. 30 The central one of these enlargements I extends up the front of the cylindrical standard or leg D in a gradually-narrowing rib E, which finally merges into the standard. The side enlargements extend up in gradually enlarging or widening ribs F G, the latter, G, extending around the rear half of the standard at its upper portion. The ribs G are ornamented by transverse inclined ribs H.

The leading feature of the design is the 40 ornamentation described.

What I claim as my invention is—

The design for a table-leg foot, substantially as herein described and shown.

In testimony whereof I affix my signature 45 in presence of two witnesses.

HENRY JOHNSON.
